ARTHUR ERNEST JERRAM, OF LEICESTER, ENGLAND, ASSIGNOR TO UNITED SHOE MACHINERY COMPANY, OF PATERSON, NEW JERSEY, A CORPORATION OF NEW JERSEY.

LEVELING-MACHINE.

1,116,071.

Specification of Letters Patent.

Patented Nov. 3, 1914.

Application filed June 1, 1911. Serial No. 630,624.

To all whom it may concern:

Be it known that I, ARTHUR ERNEST JERRAM, a subject of the King of England, residing at Leicester, in the county of Leicestershire, England, have invented certain new and useful improvements in Leveling-Machines; and I do hereby declare the following to be a full, clear, and exact description of the invention, such as will enable others skilled 10 in the art to which it appertains to make and use the same.

The present invention relates to machines for leveling the soles of boots and shoes, and more particularly to that type of machine 15 which is arranged to level the soles after they have been incorporated in the boots and shoes. Sole leveling machines of this general class as heretofore constructed have been designed upon lines conforming to 20 three separate types. The first of these types is a machine having a vibrating leveling roll which is caused to traverse over the sole and is canted first to one side and then to the other in order to give the sole the proper curvature in cross section and bed it 25 down upon the last which is carried upon a suitable shoe supporting jack. The second type of sole leveling machine employed is one wherein the last or jack and a coöperating form shaped to correspond to the desired 30 curvature of the shoe bottom in cross section have a relative rocking or oscillating movement imparted thereto in order to progressively advance the line of application of 35 the pressure in the direction of the length of the sole and secure what is termed a rolling pressure upon the shoe bottom. This is accomplished either by carrying the jack and form on the ends of opposed levers that are 40 geared together to oscillate in unison or by providing a fixed jack and a coöperating roll form which is traversed back and forth over the shoe bottom and is positively rotated to 45 preserve the proper register between the surfaces of the form and sole. The last of the 50 three types of machines in use is one in which a form shaped to correspond to the desired curvature of the sole is applied to the sole when the shoe is supported upon the jack and a direct pressure is then applied to the form in order to level the sole. Each of these types of machines has certain limitations in its application and disadvantages in its use. Machines constructed according to

the first type are relatively slow in their 55 operation and do not impart to the shoe bottom an exact predetermined shape and the pressure of the roll operating along one margin of the sole has a tendency to raise the opposite margin of the sole. In the second 60 type of machine, the disadvantages referred to in connection with the first type will be absent, but owing to the fact that different thicknesses of soles must be operated upon, the linear velocities of the surfaces of the 65 form and jack will vary and a sliding or creeping action will necessarily take place between the surface of the form and the sole. This action in some cases is so pronounced 70 that the lighter or finer grades of shoes can not be leveled upon this class of machines, as with the lighter makes of shoes, the creeping results in such distortion and damage as to spoil the finished article in the process of manufacture. Even when operating upon 75 soles of a uniform thickness, the contour of the shoe bottom in longitudinal section is such that the point of contact between the surface of the sole and form approaches and recedes to and from the fulcrum of the form 80 so that there is a variation in the relative velocities of the contacting parts of the form and sole not only at different parts of the sole of the same shoe, but altering with each 85 different shape and size of sole. A further objection to this type of machine resides in the fact that the angular turning movements of the form and jack are so great that this type cannot be employed for leveling the 90 heel seat and furthermore the projecting 95 margin of the shoe sole at the toe is turned down in an objectionable manner, more particularly on the smaller size shoes. The third type of leveling machine performs satisfactorily the leveling operation as regards 100 the objections set forth above, inasmuch as it is rapid and the shape of the sole is predetermined by the shape of the form. As a direct pressure is employed, however, which is distributed over the entire surface of the 105 sole, an extremely heavy pressure is required to secure the requisite molding and consolidation of the shoe bottom even on lighter grades of work, and as there are necessarily some slight inequalities in the stock and in the shape and form of the lasts, it is found that lasts cannot be made sufficiently strong to withstand the required pressures.

The object of the present invention is to provide a leveling machine which combines the several advantages of the different types of sole leveling machines hereinbefore described without including their attendant limitations.

With this end in view, one feature of the invention contemplates the provision in a machine of the rolling pressure type having a coöperating jack and form, of means for imparting a progressive rolling pressure to the work and for maintaining the contacting surfaces of the pressing form and work against a relative movement in the direction of the rolling pressure.

A further feature of the invention contemplates the provision with a coöperating jack and form of means to impart a relative rocking or tipping movement of slight angularity to the last and form to bring in sequence different portions of the form in contact with the corresponding portions of the shoe bottom. This movement is sufficient to apply the pressure progressively at different points along the length of the shoe bottom but is not sufficient to cause a rounding down of the toe or heel seat.

A still further feature of the invention comprises the combination in a machine of the type described of a shoe supporting member and a coöperating sole pressing member relatively movable toward and from each other, and means for oscillating or rocking one of the members about a fixed axis in order to level the shoe bottom. In the simplest and most efficient form of the invention which has yet been devised, one member is rocked relatively to the second member about an axis lying substantially in the surface of the first mentioned member.

A still further feature of the invention contemplates such an arrangement of the form and jack that a considerably less pressure is exerted at the toe end of the shoe than at the ball or heel seat.

Still further features of the invention comprise certain novel features of construction, combinations and arrangements of parts hereinafter described and claimed, the advantages of which will be apparent to those skilled in the art from the following description.

In the accompanying drawings illustrating the preferred form of the invention; Fig. 1 is a side elevation partly in section illustrating a leveling machine embodying the several features of the invention in their preferred form; Fig. 2 is a detail illustrating the mechanism for moving the jack from a receiving position into a position of presentation and showing the carrier for the jack in a receiving position with its slider retracted; Fig. 3 is a view similar to Fig. 2 and illustrating the carrier in a position of presentation with its slider retracted; Fig. 4 is a view similar to Fig. 2

illustrating the carrier in a position of presentation and with its slider moved outwardly; Fig. 5 is a detail illustrating the mechanism for alternately locking the jacks in fixed position and showing one of the jacks locked in a receiving position; Fig. 6 is a view similar to Fig. 5 and illustrating the opposite jack locked in a receiving position; and Fig. 7 is a detail illustrating a modified construction for alternately locking the jacks in a receiving position.

The machine shown in the illustrated embodiment of the invention is what is known as a twin machine; that is, duplicate sets of jacks and forms are employed and the proper movements are automatically imparted to the jacks to move them alternately from a receiving position into a position of presentation and vice versa. As the mechanism for imparting these movements, and as the construction of the jacks and coöperating forms are identical, only so much of the mechanism as is essential for a complete understanding of the construction and operation of the machine will be described in the following specification.

The machine consists generally of a frame 1 supporting upstanding carriers 2 upon the ends of which are mounted jacks 3 which are adapted to be moved alternately from a position in which the work is placed upon them, and which is termed a receiving position, into a position in alignment with the coöperating forms, and which is termed a position of presentation. The two coöperating forms, one of which is indicated at 6, are carried side by side upon a supporting lever 7, and the forms have provision for a longitudinal adjustment upon the lever 7 in order to position them accurately in the proper coöperative relation with various sized jacks. This adjustment is conveniently effected by providing each of the forms 6 with an adjustable abutment, such, for example, as the screw 11 which engages a recess formed in the lever 7 and which positions the form longitudinally and aids in retaining it in the proper position. In order to lock the opposite end of the form in position, a movable clip 8 having an undercut portion is arranged to enter a slot 9 cut in the opposite extremity of the form and serves to position the form laterally and longitudinally and hold it securely upon the lever. The movable clip 8 is carried by a screw 12 which is threaded in the lever 7 and an actuating wheel 10 serves to impart the proper rotation to the screw 12 in order to move the clip into operative position. The clip is held in place upon the screw 12 by a pair of collars which are fastened to the screw and engage the opposite ends of the clip. In order to secure a yielding pressure upon the shoe bottom and to accommodate different thicknesses of soles, the lever

7 is arranged to yield outwardly when a pressure in excess of a predetermined amount is applied. To this end, the lever 7 is pivoted to the frame of the machine at 13 and a spring 14 is interposed between the tail 15 of the lever and a fixed abutment 16 formed upon the machine frame. As will be obvious to those skilled in the art, the spring 14 is arranged to hold the forms 10 yieldingly against the thrust of the work. It will be noted upon an inspection of Fig. 1 that the end 17 of the form 6 is arranged to engage with the heel seat and that this end is nearer to the pivotal point 13 than the 15 part 18 which engages the toe of the shoe. With this relative arrangement of the form and supporting lever, considerably less pressure will be exerted upon the shoe at the toe portion where it is least required and where 20 the last is least able to withstand it, than will be exerted upon the shoe at the heel seat and shank. To enable the strength of the spring to be varied as required according to the character of the work operated 25 upon, the tail 15 of the lever is provided with a screw 20 passing therethrough, which screw bears against a cap 21 provided at one end of the spring. In order to limit the inward movement of the lever 7, an adjustable stop 22 is threadedly mounted in the 30 frame and is arranged to engage with the lower extremity of the tail 15.

As stated previously, it is desirable to impart relative rocking or tipping movements 35 to the jack and the form, which are sufficient to shift the point of application of the pressure progressively along the length of the sole. It is also desirable to secure the initial engagement of the jack and form by 40 a direct relative approach of the two and between the leveling operations to hold the jack in a receiving position conveniently accessible to the operator in order that the finished shoe may be removed therefrom and 45 a new shoe put in its place. To this end, the carrier 2 is first rocked about a fixed axis to swing the jack from the receiving position into alignment with its co-operating form. At the conclusion of the rocking movement, 50 the jack is slid longitudinally of the carrier to secure a movement of direct relative approach between the jack and form. The jack or last 3 is detachably secured in a cylindrical slider 24 in order that different 55 sized lasts may be employed in the machine. The slider is arranged to move longitudinally in a sleeve 25 forming part of the carrier 2, which is pivoted at 26 upon a lever 27. The lever 27 is fulcrumed centrally upon the frame at 28 and a stop screw 29 serves to limit the movement of the lever in one direction. In order to impart the proper longitudinal movement to the slider 24, a toggle lever comprising the links 30 60 and 31 is connected at 32 to the lower end of

the slider 24. When the toggle is broken, the slider 24 will be moved inwardly in the sleeve 25 and when the toggle is straightened, the slider will be moved in the opposite direction. To effect the breaking and straightening of the toggle, a bell crank lever 33 is pivoted at 34 upon the carrier 2 and one end of the bell crank is connected through a link 35 to the central point 36 of the toggle. The opposite end 37 of the bell crank is connected through a link 38 to the lever 39 which is pivotally connected to the frame at 28. The central point of the lever 39 is coupled to a connecting rod 40 which is provided at its opposite end with an eccentric strap 41 surrounding an eccentric 42 mounted upon a shaft 43. An intermittent rotation is imparted to the shaft 43 from a sleeve 44 by a worm 45 and worm wheel 46.

In order to determine the extent of movement of the bell crank 33 and consequently the movement of the slider 24, the carrier 2 is formed with a recess or cutaway portion 50 so arranged that the surface thereof constitutes an abutment with which the outer 55 end of the bell crank lever will engage after it has been rocked upon its center 34 to break the toggle lever with which it is connected. The recess 50 in the carrier 2 thus forms a lost motion connection between the 60 connecting rod 40 and the carrier 2, which in the preliminary movement of the bell crank lever through the operation of the eccentric 42, draws the slider inwardly in the sleeve 25. The continued movement of the 65 bell crank causes the end 37 to engage with the inner surface of the recess 50 and swing the carrier 2 about the pivot 26 in order to remove the last from a position of presentation into a receiving position. By referring 70 to Figs. 2, 3 and 4 of the drawings, the operation of this mechanism can be traced very clearly. In Fig. 2, the carrier is shown in its receiving position with the slider retracted and holding the jack in a position 75 to receive a shoe. In Fig. 3, the carrier has been rocked to bring the jack into a position of presentation in alignment with its co-operating form and in Fig. 4, the slider is shown in its outward position, with the 80 toggle straightened in order to move the jack into a pressing position. It will be noted from an inspection of Fig. 1 that the jack is held in a substantially vertical direction when in a position for receiving the 85 work and that in the position of presentation, the jack is held in an oblique direction. The jack may be arranged so that the initial 90 rocking movement of the carrier is secured either by gravity or by other suitable means, 95 thus maintaining the face of the recess 50 in contact with the end 37 of the bell crank during the movement of the carrier from the position shown in Fig. 2 to that shown in Fig. 3. In order to limit this movement 100

of the carrier and position the jack accurately in alignment with its coöperating form, a stop device is provided. This stop device preferably comprises a clip link 52 which is pivoted to the carrier 2 at 53 and is arranged to engage a projecting stud 54 mounted upon the machine frame. The link is provided with a jaw 55 having an arcual surface 56 which forms the engaging 10 face of the stop device for arresting the downward movement of the carrier, and this face engages a corresponding face 57 formed upon the stud 54. The clip link 52 is prevented from freely pivoting about the point 15 53 by a link 58 connecting the lower end of the link 52 with the central point of the lever 39.

In addition to the movement of direct relative approach between the jack and form, 20 a progressive rolling movement of slight angularity is imparted to the jack in order to perform the leveling operation proper upon the sole. This progressive rolling movement is obtained by rocking the jack about 25 a fixed axis lying substantially in the surface of the jack. In the present embodiment of the invention this axis is located in close proximity to the ball line so that the shoe is virtually swung about an axis lying 30 in the surface of the sole and midway between its ends. With this construction and mode of operation, the contacting surfaces of the work and the pressing form are maintained against a relative longitudinal movement during the pressing operation. In the 35 present construction, the rocking movement of the jack is obtained by supporting the jack at two points which are shifted in paths angularly arranged with relation to one another and which lie substantially in the arc 40 of a circle of which the fixed axis of the jack forms the center. In the illustrated embodiment of the invention this is accomplished by swinging the jack bodily upon 45 two radius links pivoted to the machine frame. These links are virtually constituted by the lever 27 and the clip link 52 which form a rigid connection between the stud 54 and pivotal points 53 when the carrier 50 is supporting the jack in a position of presentation. It will be noted from an inspection of Fig. 4 that when in this position, the pivotal point 53 alines with the pivotal connection between the bell crank 33 and link 55 38 so that the rocking of the carrier about this point will not cause any alteration of the bell crank 53 and slide actuating mechanism relatively to the carrier 2. The extent 60 of the rocking movement of the jack with this arrangement will be apparent from an inspection of Fig. 1 and it can readily be seen that this movement is extremely slight and is only sufficient to move the surface of the sole and form out of engagement where 65 the pressure is not applied. This produces

what is substantially a direct pressure over limited areas of the sole, these areas being progressively advanced from heel to toe and vice versa. Thus the advantages of the direct leveling pressure are secured without 70 its disadvantages, and as the leveling pressure is applied only over limited areas of the sole, the resultant pressure is sufficient to level the sole properly without being great enough to break down and injure the last. 75 In order to impart this compound rocking motion to the carriers, each of the levers 27 (it being understood that each of the carriers is provided with a lever 27 and actuating mechanism therefor) is connected by a 80 driving rod 60 with a floating link 61 which is operated by an eccentric 62 mounted upon a shaft 63. A continuous rotation is imparted to the shaft 63 from the main drive shaft by a worm 64 and worm wheel 65. In 85 order to enable the jacks 3 to have a rolling or tipping motion imparted thereto when the jacks are alternately moved into a position of presentation, a mechanism common to both of the jacks is employed. 90

It will be noted that the rods 60 connect the lower ends of the levers 27 with opposite ends of the floating link 61 and a stop mechanism is provided for alternately locking the lower ends of the levers 27 while the 95 jacks are held in a receiving position. When the lower end of one of the levers is locked, the corresponding end of the link 61 is likewise locked in position through the rigid connection formed by the driving 100 rod 60. This insures that the full throw of the eccentric will be exerted upon the lever 27 which is free, and the lower end of this lever will be oscillated accordingly 105 in order to impart the proper movements to the jack.

The stop mechanism conveniently comprises a rocker 70 pivotally mounted upon the frame at 71 and provided with a pair of laterally projecting locking arms 72. Although in the illustrated embodiment of the invention a pair of arms 72 are employed, it is to be understood that if so desired, a single arm may be employed which is arranged to engage alternately with the lower ends of the two levers 27. The two arms 72 lie in the same lateral plane so that only one arm is shown in Figs. 5 and 6 of the drawing. The lower ends of the levers 27 are provided with shouldered portions 69 arranged to engage the outer ends of the arms 72 and lock the levers in position. The rocker 70 is oscillated from one position to another by an anchor rod 73 which is provided with a head 74 having two undercut 120 portions 75 and 76. The anchor rod 73 is pivotally connected at 77 to a treadle 78 employed for starting the machine, and the anchor rod is arranged to swing about this pivotal connection so that one or the other 125 130

of the undercut portions 75 or 76 will engage with one or the other of two abutments 79 and 80 respectively formed on the rocker 70. In order to hold the arms 72 in either 5 of the extreme positions into which they may be moved, a ball-ended spring pressed strut 82 is interposed between the machine frame and the rocker 70. After the treadle has been depressed to turn the rocker and 10 lock one of the levers 27 in position, it is desirable that means be provided for automatically shifting the position of the anchor rod 73 into engagement with the opposite abutment. For example, assuming that the 15 undercut portion 75 engages with the abutment 79 and the treadle is then depressed, the outer end of the arm 72 will be moved upwardly and engage with the lower end of one of the levers 27. Upon a release of the 20 treadle it is desirable that the anchor rod be automatically shifted in position so that the undercut portion 76 will engage with the abutment 80 upon the next succeeding movement of the treadle. To this end, a 25 spring 83 connects the rocker 70 with a projection 84 formed upon the anchor rod 73 and this spring is so arranged that when the rocker 70 is moved by the anchor rod into either of its extreme positions, the 30 spring is bowed and tends to impel the anchor rod to engage with the opposite abutment, through which the position of the rocker is reversed. To enable a further motion of the treadle and insure that the 35 rocker will be moved to its extreme position, notwithstanding variations in the cycle of the machine, the pivotal connection 77 is in the form of a slot formed in the end of the anchor rod 73 and a pin 85 is fixed upon 40 the treadle 78 and connected to the rod 73 by a spring 86, the spring normally holding the pin at one extremity of the slot. In the operation of this stop mechanism, when the treadle 78 is depressed, one of the undercut portions 75 or 76 of the anchor rod 73 45 engages the corresponding abutment 79 or 80 formed on the rocker 70 and turns the latter into a position in which one of the arms 72 engages and holds the shouldered 50 portion 69 formed upon the corresponding lever 27 and thereby causes the second lever to be oscillated through the eccentric 62. As the rocker 70 turns, the flexible rod or 55 spring 83 will shift the anchor rod into a position to cause the opposite undercut surface to engage with its corresponding abutment upon the next depression of the treadle and thus bring the second lever into operation.

In the modification shown in Fig. 7 of 60 the drawings, the stop mechanism is power actuated instead of being actuated directly from the treadle. To this end, a bell crank lever 90 is pivoted to the frame of the machine at 91. One arm of the lever is bifurcated forming arms 92 which are arranged

to engage in the usual manner with the shouldered portions 69 formed upon the lower ends of the levers 27. In order to move either of the arms 92 into or out of engagement with the respective ends of the 70 levers 27, the bell crank 90 is connected to the lever 39 by means of a rod 93. This rod 93 is pivotally connected to the bell crank 90 at 94 and has a sliding connection with the lever 39 at 95, the springs 96 and 97 being mounted on the link upon opposite sides of the connection 95 in order to maintain a yielding operative connection with the lever 39. It will be noted with this construction that when the lever 39 moves 80 in one direction; for example, when moving its carrier and last from a position of presentation to a receiving position, the bell crank 90 will be moved about its pivotal connection 91 and one of the arms 92 will engage with the end of one of the corresponding levers 27 in a similar manner and for the same purpose as described with reference to the rocker 70 and arms 72. When the lever 39 is moved in the opposite direction; that is, when moving its carrier from a receiving position to a position of presentation, the opposite action will take place, and one of the arms 92 will engage with the lower end of the second lever 27.

It will now be apparent that the link 58, in addition to guiding the clip link 52 during the movement of the clip link into a locking position, serves as an operating connection for automatically disengaging the 100 clip link upon the return movement of the jack from a pressing position into a receiving position. The initial movement of the lever 39 to break the toggle lever will thrust the clip link 52 in such a direction as to 105 free its jaw from the stud 54. The continued movement of the lever 39 then causes the end 37 of the bell crank lever 33 to engage with the surface of the recessed portion 50 as hereinbefore set forth and move 110 the jack bodily into a receiving position.

In order to place the starting and stopping of the machine under the control of the operator, the treadle 78 is fulcrumed upon the frame at 98 and is pivotally connected at its rear end to a rocker frame 99 through an arm 100. The frame 99 is fulcrumed upon the machine frame at 101 and is provided with two other arms 102 and 103. The arm 102 actuates a clutch tripping gear of a suitable form which is arranged to move a cone clutch member 104 into engagement with a co-operating clutch face 105 formed upon the inner surface of the driving pulley 106. The cone clutch member 104 125 is splined to the sleeve 44 to which the worm gear 45 is locked. Thus upon the engagement of the clutch members 104 and 105, the eccentric 42 is operated to move its corresponding jack either into or out of a press- 130

ing position. The second arm 103 of the frame 99 is provided with a cam roll 108 which operatively engages with a peripheral cam 109 fastened to one face of the worm wheel 45. The cam 109 is provided with recesses 110 disposed diametrically opposite so that after the shaft 43 has made a half revolution, the cam roll 108 will be moved into one of the recesses 110 and thus move 5 the arm 102 to disengage the clutch members 104 and 105. A suitably arranged spring (not shown) may be employed for normally moving the rocker frame 99 to disengage the clutch members. In addition 10 to intermittently operating the eccentric 42, the drive pulley 106 continuously operates the shaft 63 and eccentric 62 mounted thereon. To this end, a spider 111 is keyed to the main drive shaft 112 and the spider is locked against rotation relatively 15 to the drive pulley 106 by a plurality of slide pins 113 engaging with a series of holes formed in the arms of the drive pulley 106.

The operation of the machine will no 20 doubt be understood from the foregoing description, but for the sake of a clear understanding of the invention it may be briefly re-stated as follows:—It will be assumed that the machine is in a position with one 25 of the jacks in a receiving position and the opposite jack in a position of pressure. After the finished work has been removed from the first mentioned jack and a new shoe placed thereon, the treadle is depressed 30 to engage the clutch members 104 and 105 and actuate the eccentric 42 to move the jacks in opposite directions into and out of a pressing position respectively. The jacks simultaneously reach pressing and 35 receiving positions and the clutch members are then disengaged automatically. The operation of the treadle through the anchor rod 73 also causes the rocker 70 to be turned on its center so that it releases one of the 40 levers 27 and engages and holds the second lever 27. The continuously operating eccentric 62 then serves to impart an oscillatory motion to the lever which has been released in order to rock the jack which is held 45 in a pressing position.

While it is preferred to employ the specific construction and arrangement of parts shown and described, it will be understood that this construction and arrangement is 50 not essential except so far as specified in the claims and may be changed or modified without departing from the broader features of the invention.

The invention having been described, 55 what is claimed is:—

1. A sole leveling machine having, in combination, a shoe supporting jack, a pressing form cooperating therewith, and means for relatively rocking the jack and form to im- 60 part a progressive rolling pressure to the

sole and for maintaining the contacting surfaces of the pressing form and work against a relative movement in the direction of the rolling pressure during the leveling operation, substantially as described. 70

2. A sole leveling machine having, in combination, a shoe supporting member and a co-operating sole pressing member relatively movable toward and from each other, and means for rocking one of the members about 75 an axis lying substantially in the surface of the member to impart a progressive rolling pressure to the shoe sole, substantially as described.

3. A sole leveling machine having, in combination, a shoe supporting member and a co-operating sole pressing member relatively movable toward and from each other, a pair of radius links supporting one of the members, and means for oscillating the links to 80 rock the member and level the sole, substantially as described. 85

4. A sole leveling machine having, in combination, a shoe supporting member and a co-operating sole pressing member movable toward and from each other, a carrier pivotally supported at two points, and means for shifting the supporting points of the carrier in paths angularly arranged with 90 relation to one another to secure a relative rocking motion of the two members, substantially as described. 95

5. A sole leveling machine having, in combination, a pressing form, a shoe supporting jack, means acting automatically for 100 first moving the jack from a receiving position into a position of presentation in alignment with the pressing form for next imparting a movement of direct relative approach to the jack, and means for rocking 105 the jack relatively to the form when in a position of pressure, substantially as described.

6. A sole leveling machine, having, in combination, a pressing form, a shoe supporting jack co-operating therewith, a carrier supporting the jack, and means acting automatically for rocking the carrier to bring the jack into a position of presentation, for imparting a longitudinal movement to the 110 jack relative to the carrier to bring the jack and form into a position of pressure, and for oscillating the jack relative to the form when in a position of pressure to level the shoe sole. 115

7. A sole leveling machine having, in combination, a pressing form, a carrier, a shoe supporting jack slidably supported in the carrier, a toggle connected to the jack, a stud, and means for oscillating the carrier 120 from a receiving position into engagement with the stud and for thereafter actuating the toggle to move the jack relatively to the carrier, substantially as described. 125

8. A sole leveling machine having, in com- 130

bination, a sole pressing member, a shoe supporting jack coöperating therewith, intermittently operated means for moving the jack from a receiving position into a position of presentation, continuously operated means for rocking the jack, and means under the control of the operator arranged to start the intermittently operated means and to simultaneously connect the continuously operated means with the jack, substantially as described.

9. A sole leveling machine having, in combination, sole pressing forms, shoe supporting jacks coöperating therewith, means acting automatically to move the jacks alternately into and out of a pressing position, and means for imparting a rocking movement to each of the jacks when the jack is moved into a pressing position, substantially as described.

10. A sole leveling machine comprising a pair of shoe supporting jacks, continuously operated means for rocking the jacks, and a single control means constructed and arranged upon each actuation by the operator to automatically connect alternate jacks to the continuously operated means, substantially as described.

11. A sole leveling machine comprising a pair of shoe supporting jacks, a supporting lever for each jack, means under the control of the operator for alternately locking one of the levers and continuously operated means for oscillating the second lever upon the locking of the first lever, substantially as described.

12. A sole leveling machine comprising a pair of shoe supporting jacks, a supporting lever for each jack, means under the control of the operator for alternately locking one of the levers, a floating link, means for continuously oscillating the link and connections between the opposite ends of the link and the lower ends of the supporting levers, substantially as described.

13. A sole leveling machine having, in combination, a shoe supporting member and a coöperating sole pressing member relatively movable toward and from each other, means for yieldingly supporting one member, and means for rocking one of the members about an axis lying substantially in the surface of the member to impart a progressive rolling pressure to the shoe sole, substantially as described.

14. A sole leveling machine having, in combination, a pressing form, a shoe supporting jack coöperating therewith, a carrier for the jack, a toggle lever connected to the jack, an abutment on the carrier, and

means for first breaking the toggle to move the jack relatively to the carrier and for thereafter engaging the abutment to oscillate the carrier and move the jack into a receiving position, substantially as described. 65

15. A sole leveling machine comprising a pair of shoe supporting jacks, a supporting lever for each jack, a pair of locking arms, and means under the control of the operator for oscillating the arms to alternately engage the ends of the supporting levers and lock the levers in a fixed position, substantially as described. 70

16. A sole leveling machine comprising a pair of shoe supporting jacks, a supporting lever for each jack, a rocker, arms extending from the rocker, and arranged to engage the supporting levers, a treadle, and connections between the treadle and rocker for turning the rocker in opposite directions upon each 80 succeeding depression of the treadle, substantially as described.

17. A sole leveling machine comprising a pair of shoe supporting jacks, a supporting lever for each jack, a rocker, operative connections between the rocker and supporting levers, a treadle, and an anchor rod for operatively connecting the treadle with the rocker and for turning the rocker in opposite directions upon each succeeding depression 90 of the treadle, substantially as described.

18. A sole leveling machine comprising a pair of shoe supporting jacks, a rocker, operative connections between the rocker and jacks, abutments formed on opposite ends of 95 the rocker, an anchor rod, and means for shifting the position of the anchor rod to engage alternate abutments upon each succeeding operative movement of the rod, substantially as described. 100

19. A sole leveling machine having, in combination, a shoe supporting member, and a coöperating sole pressing member relatively movable toward and from each other and arranged to secure a considerably less 105 pressure at the toe end of the shoe than at the ball and heel seat, and means for rocking the members to level the sole of a shoe on the jack, substantially as described.

20. A sole leveling machine having, in 110 combination, a sole pressing form, a pivoted lever supporting the form, with the heel end of the form nearer to the fulcrum than the toe end, a shoe supporting jack, and means for imparting a rocking motion to the jack 115 to level the shoe, substantially as described.

ARTHUR ERNEST JERRAM.

ELEANOR RUSSELL.

Corrections in Letters Patent No. 1,116,071.

It is hereby certified that in Letters Patent No. 1,116,071, granted November 3, 1914, upon the application of Arthur Ernest Jerram, of Leicester, England, for an improvement in "Leveling-Machines," errors appear in the printed specification requiring correction as follows: Page 3, line 77, for the word "povotally" read *pir-otally*; page 4, line 57, for the reference-numeral "53" read *33*; page 6, line 76, first occurrence, for the word "in" read *an*; same page, line 105, strike out the word "means"; and that the said Letters Patent should be read with these corrections therein that the same may conform to the record of the case in the Patent Office.

Signed and sealed this 24th day of November, A. D., 1914.

[SEAL.]

R. F. WHITEHEAD,
Acting Commissioner of Patents.
